UNITED STATES PATENT OFFICE.

FRED J. GAERTNER, OF MAPLEWOOD, NEW JERSEY.

DESIGN FOR COMBINATION JEWEL MOUNTING AND GEM.

Application filed September 13, 1927. Serial No. 23,400. Term of patent 7 years.

To all whom it may concern:

Be it known that I, FRED J. GAERTNER, a citizen of the United States, residing at Maplewood, in the county of Essex and State of New Jersey, have invented a new and original Design for Combination Jewel Mounting and Gem, of which the following is a specification, reference being had to the accompanying drawings, forming part thereof.

In said drawings, Figure 1 is a side edge elevation and Figure 2 is a top plan or face view of a combination jewel mounting and gem showing my new design.

I claim:

The ornamental design for combination jewel mounting and gem as shown.

Dated this 8th day of September, 1927.

FRED J. GAERTNER.
